UNITED STATES PATENT OFFICE.

OSCAR O'NEAL, OF FREMONT, MICHIGAN.

AUTOMOBILE-LAMP.

1,071,785.

Specification of Letters Patent.

Patented Sept. 2, 1913.

Application filed November 8, 1912. Serial No. 730,287.

To all whom it may concern:

Be it known that I, OSCAR O'NEAL, a citizen of the United States, residing at Fremont, in the county of Newaygo and State 5 of Michigan, have invented new and useful Improvements in Automobile-Lamps, of which the following is a specification.

This invention relates to lamps for automobiles and other self-propelled vehicles, 10 the object being to provide a lamp of the class ordinarily known as headlights, embodying a novel construction and arrangement of parts, by means of which the rays of light are transmitted laterally from the 15 lamp, as well as directly ahead, the stronger rays being, however, directed through the front of the lamp, so as to illuminate the roadway in front of the machine.

One of the principal objects of the present 20 invention is to provide the lamp with a series of removable transparent panels, usually of glass, combined with a novel arrangement of hinged door and a bar which is common to both panels, whereby the latter are securely held in place when the lamp 25 is closed.

With the above and other objects in view, the invention consists in the construction, 30 combination and arrangement of parts, as will be hereinafter more fully described, illustrated in the accompanying drawings, and pointed out in the claims hereunto appended.

In the drawings: Figure 1 is a perspective 35 view of a lamp, embodying the present invention. Fig. 2 is a horizontal section through the same. Fig. 3 is a vertical cross section through the lamp, looking toward the rear. Fig. 4 is a vertical fore and aft section through the lamp. Fig. 5 is a detail perspective view of the door detached, showing the two door sections separated.

The lamp contemplated in this invention comprises a suitable case, having a top 1, a 45 bottom 2, a back 3, and a side 4, the latter being rounded or semi-cylindrical in shape, and having secured to the inside thereof upper and lower grooved guides 5, which receive the top and bottom edges of a reflector 50 6 which is thus made removable, the upper and lower guides being connected by and formed integrally with a sheet metal backing piece 7 which forms a protection for the reflector. The bottom 2 is provided with 55 air inlet perforations 8 covered on the inside by hoods 9 provided with a large number of

perforations 10 to allow the necessary draft of air through the bottom of the case.

The top 1 of the case is formed with a large vent hole 11 covered by a hood 12 having formed in the opposite sides thereof perforations 13 to allow the smoke and heat to escape.

14 designates the usual acetylene burner arranged within the lamp and supported 65 on the bottom thereof by an upstanding tube 15 passing through the bottom of the lamp and provided with a nipple 16 adapted to receive rubber tubing, through which the acetylene gas is lead to the burner in the 70 usual way.

Within the lamp case and, at the back thereof is a combined concavo-convex lens holder and reflector 17 having arranged in front thereof a double convex lens 18, the 75 combined holder and reflector being secured to the back of the lamp and embodying a split lens clamping band 18 adapted to clamp the lens in place over the front of the reflector. This clamping band is provided with outwardly extending ears 19, through which passes a clamping bolt 20 provided with a nut 21 having sockets 22 in the outer edge thereof adapted to receive a pin or spanner, by means of which said 85 nut may be turned for loosening or tightening the band.

The outer side of the lamp is cut away to form a window opening 23, and along the top and bottom edges of the window opening and at the rear edge thereof are sheet metal guides 24 adapting a glass panel 25 to be removably fitted therein. The guides at the top and bottom of the window opening are obliquely slit, as shown at 26, to 90 95 form a plurality of yielding fingers 27 which serve to engage the glass panel adjacent to the top and bottom edges thereof for holding said panel in place and preventing the same from rattling. At the front of 100 the case is a hinged door, comprising the main section 29 and a smaller section 30 which is hinged directly to the lamp case. Upon its inner side, the main section 29 is provided at the top and bottom with guides 105 31 for a removable glass panel 32, and the said guides are formed with inclined or oblique slits, thereby forming series of spring fingers 33 which serve to bind the glass panel in place and prevent the same 110 from rattling.

The smaller section 30 of the door em-

bodies top and bottom sockets 34 which receive the adjacent portion of the main section 29 of the door, the two sections 29 and 30 being secured together by screws inserted 5 through the holes 34', as shown.

35 designates a bar which connects the top and bottom sockets 34, the said bar 35 being L-shaped in cross section so as to engage the outer end of the glass panel in the 10 door and prevent the same from escaping from its position. When the door is closed, the bar 35 lies across the edge of the side 15 glass panel, and thus forms a common stop or bar for the two glass panels, when the door of the lamp is closed, preventing the accidental dislodgment of both of said panels. By opening the door and detaching the main section 29 of the door, both 20 glass panels may be easily slid out of place and cleaned or renewed when broken.

The lamp is equipped at opposite sides with attaching lugs 36 having openings 37 to receive the forked ends of the usual lamp 25 supporting bracket now in common use on automobiles and similar vehicles.

What is claimed is:

1. A vehicle lamp, comprising a casing,

a removable side glass panel slideable in guideways opening out at the front of the casing, a door hinged to the front of the 30 casing on a vertical axis, a glass panel slideable in guideways on said door and also removable, and a panel retaining bar on the door common to both the side and door panels when the door is closed. 31

2. A vehicle lamp, comprising a casing, a removable side glass panel slideable in guideways opening out at the front of the casing, a door hinged to the front of the 35 casing on a vertical axis, a glass panel slideable in guideways on said door and also removable, and a panel retaining bar on the door common to both the side and door panels when the door is closed, the door embodying separable sections, one of which 40 carries the panel retaining bar.

In testimony whereof I affix my signature in presence of two witnesses.

OSCAR O'NEAL.
